UNITED STATES PATENT OFFICE

FRANKLIN B. HUNT, OF CHICAGO, ILLINOIS, ASSIGNOR TO THE LIQUID CARBONIC CORPORATION, OF CHICAGO, ILLINOIS, A CORPORATION OF DELAWARE

REFRIGERATING SYSTEM

Application filed August 15, 1930. Serial No. 475,416.

The object of my invention is to provide a refrigerating system comprising a plurality of heat-absorbing elements so connected to a single regenerator that the various heat-absorbing elements, when properly placed in independent refrigerating chambers, may have different minimum operating temperatures.

The present invention is a development of 10 the invention forming the subject matter of my Patent Number 1,746,896.

The accompanying drawing diagrammatically illustrates my invention as embodied in a refrigerating system of the mechanical 15 compression type. In the drawing, 10 indicates a mechanical compressor having the suction line 11 and the discharge line 12 which leads into a condenser 13. Leading from condenser 13 is the refrigerant discharge line 14 20 from which lead branches 15, 16, 17 (etc.) to heat-absorbing units 18, 19, 20 (etc.), respectively, of the constant liquid-level type, commonly referred to as "boilers," the discharge end of each of said branches, with- 25 in its respective boiler, being controlled by a float-controlled valve V dependent upon the liquid level in the boiler. In each branch 15, 16, 17, is an expansion valve E, of common and well known construction.

30 A portion of branch 15, between expansion valve E and boiler 18, is passed through a refrigerating chamber 30 separate and distinct from the refrigerating chamber 31 in which boiler 18 is placed. Similarly a portion 35 of branch 16 is passed through the refrigerating chamber 32 which is isolated from the refrigerating chamber 33 in which boiler 19 is placed, and similarly a portion of branch 17 is passed through a refrigerating chamber 34 isolated from the refrigerating chamber 35 in which boiler 20 is placed.

Leading from the vapor space of boiler 18 to suction pipe 11, through a control valve C of common form is a pipe 36. Similarly 45 a pipe 37 leads from the vapor space of boiler 19 through a control valve C' to pipe 11. The inlet end of pipe 11 communicates with the vapor space of boiler 20. A control valve, similar to valve C and C', may be 50 placed in pipe 11, if desired, between boiler

20 and the junction with pipe 37, but such a control valve is not necessary.

The control valves C, C', are of well known type and construction such that reduction of pressure upon the discharge side below a 55 desired minimum will result in a closing of the valve so that pressure reduction on the inlet side of the valve may not be carried below a desired minimum.

The expansion valves E are of the well known type and construction such that the pressure of liquid refrigerant discharged therethrough will be less than the supply pressure and said valves are adjustable so that any desired difference in pressure may 60 be obtained.

Control mechanism M of the well known type is provided for automatically breaking the energizing circuit of the motor of the compressor 10 when it has reduced the vapor pressure in boiler 20 to a desired minimum, and for automatically closing said circuit whenever the vapor pressure in boiler 20 exceeds a desired maximum. With a volatile refrigerant, such for instance as SO₂, the 70 use of which is contemplated in the present apparatus, the capacity of abstraction of heat from a surrounding medium is dependent upon the pressure under which the liquid refrigerant is normally maintained. 75 In other words, such a liquid refrigerant at a given pressure has a normal temperature so that the liquid refrigerant will volatilize and abstract heat from the surrounding medium until the temperature of the surrounding medium has been reduced to a temperature substantially equal to the normal temperature of the refrigerant at the pressure at which volatilization ceases.

In operation valves E are set to supply 80 refrigerant, through their respective pipes 15, 16 and 17, to the respective boilers 18, 19 and 20, at a slightly higher pressure than the normal pressure at which volatilization is to cease in said boilers; control valves C, 85 C' are set so that the vapor pressure in their respective boilers 18 and 19 may not be reduced by the compressor below desired minimums (which may be different for the two boilers); and the automatic starting and 90

stopping mechanism M will be so set that, when the vapor pressure in the suction line 11 increases beyond the desired maximum, normal working pressure of boiler 20, the compressor will be started, and whenever the compressor has reduced the vapor pressure in boiler 20 below the normal desired working pressure the compressor will be stopped.

10 The minimum attainable temperatures in the refrigerating compartments 30, 32 and 34 will be dependent upon the settings of the respective expansion valves E. The minimum attainable temperatures in the refrigerating chambers 31, 33 and 35 will be dependent upon the settings of the control valves C and C' and of the automatic starting and stopping mechanism which controls the compressor.

15 The minimum temperatures attainable in chambers 30, 32 and 34 will be respectively higher than the minimum temperatures attainable in chambers 30, 33 and 35.

20 By this arrangement the heat-absorbing elements (pipes 15, 16 and 17 in chambers 30, 32 and 34 respectively and boilers 18, 19 and 20 in chambers 31, 33 and 35 respectively) may be constantly supplied from a single source with adequate amounts of liquid refrigerant, each of said heat-absorbing elements having a predetermined refrigerating value, as to minimum attainable temperatures, so that different refrigerating effects may be attained through a wide range by 25 the operation of a single regenerating unit i. e. the compressor and condenser 10—13.

I claim as my invention:

1. A refrigerating system comprising two boilers of the constant liquid-level type, a 30 compressor, connections between the vapor spaces of said boilers and the suction side of the compressor, one of said connections comprising a control valve limiting the suction effect of the compressor on the associated boiler, a refrigerant supply pipe between said boiler and the condenser, means controlled by liquid-level in each boiler for controlling refrigerant flow into said boiler, an expansion valve in each supply pipe, four relatively isolated refrigerating chambers in two of which the boilers are mounted and two of which are respectively traversed by portions of the two supply pipes between their respective expansion valves and boilers, 35 and means dependent upon pressure in boiler vapor space for starting and stopping the compressor.

2. A refrigerating system comprising two boilers of the constant liquid-level type, 40 means for extracting exhausted refrigerating medium from said boilers and thereby reducing pressure within said boilers, means for limiting the effect of said pressure-reducing means relative to one of said boilers, 45 means connected to the discharge side of

said pressure-reducing means for increasing the pressure in the medium extracted from the boilers, a condenser receiving said medium from said pressure-increasing means, pipes connecting the discharge side 70 of said condenser with each of said boilers, an expansion valve in each of said pipes, two isolated chambers each traversed by a portion of one of said pipes between its expansion valve and boiler, means controlled by liquid-level in each boiler for controlling flow of refrigerating medium into the boiler, and two isolated chambers each containing one of the boilers.

3. A refrigerating system comprising two 75 boilers of the constant liquid-level type, a compressor, connections between the vapor spaces of said boilers and the suction side of the compressor, a refrigerant supply pipe between said boiler and the condenser, means controlled by liquid-level in each boiler for controlling the refrigerant flow into said boiler, an expansion valve in each supply pipe, four relatively isolated refrigerating chambers in two of which the boilers are 80 mounted and two of which are respectively traversed by portions of the two supply pipes between their respective expansion valves and boilers, and means dependent upon pressure in boiler vapor space for starting and stopping the compressor.

In witness whereof, I, FRANKLIN B. HUNT, have hereunto set my hand at Chicago, Illinois, this 31st day of July, A. D. one thousand nine hundred and thirty.

FRANKLIN B. HUNT.
